OF 17,503

DESIGN.

—o—
W. L. JACOBS.

CARPET.

No. 17,503.

Patented July 26, 1887.

UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 17,503, dated July 26, 1887.

Application filed June 18, 1887. Serial No. 241,808. Term of patent 3½ years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 My design consists of a number of figures grouped together in an irregular manner.

Figure A consists of a number of diamond-shaped forms with indented outlines and pendent parts irregularly massed and connected 20 and ornamented with small geometric work.

Figure B consists of two central crown-shaped forms, one of them reversed, a cross-shaped form on one side and a cone-shaped form on the other side, all with indented outlines, and partly ornamented with small figures.

Figure C is a slender curving figure with a cross form at one end and smaller projections along its edges, as shown, and is ornamented 30 with small geometric forms.

Figure D consists of a number of diamond-shaped forms with deeply indented edges irregularly grouped with pendent diamond forms, ornamented with small geometric work.

Figure E is a group of two triangular forms, 35 a diamond-shaped form, and a crown-shaped form with serrated outline, and with an ornamentation of small geometric work.

Figure F consists of two parts, one resembling in outline a spreading tree, the other 40 being an irregular figure with indented outline, both being ornamented with small geometric work.

Figure G consists of a number of forms having something of an oval shape, though with 45 indented outline, massed together irregularly and ornamented with small geometric work.

Figure H is an irregular figure having an open shrub-like form at the top, the rest of the figure being massed or bunched together, 50 as shown.

What I claim as new, and desire to secure by Letters Patent, is—

The design for carpets, consisting of the design substantially as shown.

W. L. JACOBS.
